JOHN L. SELLAR, OF BALTIMORE, MARYLAND, ASSIGNOR OF TWO-THIRDS TO HENRY CASTELBERG, OF BALTIMORE, MARYLAND.

NON-REFILLABLE BOTTLE.

1,108,099.

Specification of Letters Patent. Patented Aug. 18, 1914.

Application filed June 10, 1913. Serial No. 772,800.

To all whom it may concern:

Be it known that I, JOHN L. SELLAR, a citizen of the United States, residing at Baltimore, in the State of Maryland, have invented certain new and useful Improvements in Non-Refillable Bottles, of which the following is a specification.

This invention relates to a non-refillable bottle.

10 The object of the invention is to provide improved means for preventing bottles that have been emptied of liquid contents, and which bear well known names, brands or labels, from being refilled with inferior imitations of the genuine liquid originally contained in the bottle. Heretofore in using bottles of this character, where a valve is employed, it has been found that the liquid contents of the bottle, by wetting the valve 15 and valve-seat when the bottle is tilted, will frequently have the effect, after such bottle has stood upright for a time, to stick the valve tightly to its seat. When this has occurred the valve will not open when the bottle has been tilted, and of course liquid will not pour from a bottle thus disabled. An object therefore of this invention is to provide 20 valved bottles with means whereby, when a person is about to dispense or pour out liquid, he may first loosen and move the valve or valves to insure that the valve will open by tilting the bottle.

The several parts comprising the mechanical means which prevent refilling the bottle, 25 and also the parts which enable a stuck valve to be loosened, should be made preferably of porcelain, because such material is innocuous to liquids of any kind. A cap plug is provided which closes the bottle mouth and 30 which is so arranged with respect to the valve that by moving the cap plug a valve may be moved and if stuck will be loosened.

In the drawing which illustrates the construction of the improved device, Figure 1 is 35 a vertical section of the neck of a bottle and the mechanical parts inclosed in the neck, and shows the cap in closed position on top. Fig. 2 is a top view of the bottle neck as seen when the cap plug has been removed. Fig. 40 3 is a horizontal cross-section of the bottle

neck on the line 3—3 showing the movable weight. Fig. 4 is a horizontal cross-section on the line 4—4 showing the bottle-neck and part of the float-valve. Fig. 5 is a perspective view of the float valve, after the buoyant 45 or cork part has been removed.

The bottles to which this improvement is applicable may be of any well-known shape, and should have a neck whose throat or passage is substantially straight.

A tubular porcelain shell comprises three sections, *a*, *b*, *c*, which are made as separate pieces, and when assembled inclose the valve and other parts—the two lower sections of the said shell being inserted in the bottle neck. 50 The top section, *a*, of the tubular shell projects above the bottle-neck, 1, and may rest thereon. This top section has an open center or mouth, 2, that receives the plug, 3, that depends from the cap, 4; a cork sleeve, 5, surrounds the plug and when the bottle is closed this sleeve fits snugly within the said mouth, 2, and the cap, 4, and its plug, 3, may be turned or rotated. The lower side of the plug, 3, has a square socket, 13, which 55 serves a purpose that will be presently explained. The top section, *a*, also has cross-wise of its mouth a horizontal diaphragm, 6, provided with a round center opening, 7, and around its largest part is provided with a 60 plural number of segment-shaped openings, 8, from which latter the liquid will pour. The diaphragm serves as a baffle. The said center-opening, 7, is closed by a rotatable spindle, 9, having a squared upper end, 10, 65 and a squared lower end, 11. This round spindle also has a surrounding flange, 12, that sustains the spindle. When the cap, 4, is in its closed position, as in Fig. 1, the socket, 13, fits down over the square upper 70 end, 10, of the rotatable spindle. It will be seen that if the cap, 4, that closes the bottle should be rotated by a person's hand, the effect will be to cause the spindle, 9, to also rotate.

The interior of the tubular porcelain shell has an inward projecting annular flange, 34, below the said segment-shaped openings, 8; this flange will prevent a wire or other instrument that might be inserted downward 75

through either of said openings, 8, from reaching any movable part within the tubular shell.

The interior chamber space of the second section, *b*, incloses both a float valve, 14, and a movable weight, 15. The movable weight has around its circumference a number of vertical studs, 16, which contact loosely with the inner surface of the shell, and these studs form around the weight ample spaces, 17, through which liquid in the bottle may pass out. The weight, 15, is made of porcelain and has a square vertical opening, 18, entirely through its center. The upper part of this opening receives the square lower end, 11, of the rotatable spindle 9, and the lower part of the square opening receives the upper projecting square end, 19, on the stem, 21, of the float-valve, which latter is thus loosely connected with the weight, 15. The said weight has a limited up-and-down or sliding movement independently of the valve, 14, without disconnecting therefrom but the weight can rotate only when the valve also rotates. The structure of this float-valve is shown in Figs. 1, 4 and 5. The valve is circular like a disk and has lateral prongs, 22, around its circumference; the stem, 21, projects upward from the disk part of the valve, 14, and a cylindric piece of cork, 23, like a sleeve, takes tightly around the lower part of said stem and sets on top of the disk part; this cork has sufficient buoyancy to cause the said valve to float in liquid when the weight, 15, is not resting on the cork. The upper end, 19, of this valve-stem projects above the cylindric buoyant body, 23, and loosely enters the opening in the weight, 15.

If an empty bottle should be inverted the valve, 14, would unseat and open the port, 20; if, under these conditions, an attempt should be made to refill the empty bottle with liquid by using a tube and pump, or by other means, the result would be that when liquid entered through the nozzle, (the bottle being upside down,) and surrounded the cork and valve, 14, the buoyancy of the cork, 23, would lift the valve and close the port, 20.

From the foregoing description it will be understood that provision is here shown for a mechanical connection between the top cap, 4, that closes the mouth of the bottle, and the valve, 14, that closes the port, 20. By this mechanical connection when a person is about to pour liquid from the bottle, he may first loosen the valve, 14, on its seat to overcome any sticky or cohesive condition that might otherwise keep the valve on its seat, and then on tilting the bottle the said valve will certainly freely open or unseat, and thus a difficulty that has heretofore been experienced is overcome.

It should be stated that the spindle, 9, im-

mediately below the diaphragm or baffle, has a groove, 35, around its exterior; and a ring, 36, has a split or cut that enables it to be sprung open and take position into the said groove, 35; the entire circumference of this ring projects from the groove, 35, below the baffle and thereby the ring prevents the spindle, 9, from being lifted, raised or removed from the said baffle.

The upper portion of the third or lower section, *c*, of the tubular shell has its exterior reduced in size, as at, 37, and this smaller end is slipped into and tightly fits the lower end of the second section, *b*, as shown in Fig. 1. The interior of the lower section, *c*, comprises a circular chamber whose upper end is reduced as at, 24, and in the said reduced part is the top opening or valve-port, 20, which communicates with the chamber of the second section above. A ring, 25, has a relatively large center opening or port, 26, and this ring closes the bottom end of the third shell section, *c*. A gravity valve, 38, occupies the chamber of the said lower section and closes the port, 26, at the lowermost part of the chamber. This valve has a center upward-projecting stem, 39, whose upper end enters the lower part of the valve-port, 20, directly about it; but as the diameter of said stem is much smaller than said valve-port the flow of liquid outward is not interfered with. The advantage of this high stem is that if the bottle should be upset the high stem, 39, with its upper small end in the large port, 20, will prevent the valve from reversing its position relative to the chamber it occupies, and thus insures that the valve will be restored properly on its seat and close the port, 26, when the bottle shall be again standing on its bottom. The said valve, 38, is also provided with wings, 40, which when the bottle is greatly tilted, or turned upside down, will contact with the reduced portion, 24, at the upper end of this lower chamber and still allow liquid to flow out.

Each valve, 14, and, 38, has a concave bottom, 31, that forms around the circumferential edge at the bottom of the valve a circular bead or seat, 32, which construction minimizes the liability of the valve-bottom to stick fast to the seat around the port. These valves, when the bottle stands upright, will automatically seat themselves when the bottle stands upright.

No mechanical means connecting from the top cap, or other part adjacent the bottle-mouth or nozzle, to the lowermost valve, 38, is shown, for the reason that this particular valve, if it should stick on its seat, 125 can be loosened by tilting the bottle suddenly and thereby cause the liquid to be thrown directly against the bottom of the valve, 38, and force it off its seat.

To assemble the parts of this device, the 130

upper or nozzle section, *a*, (of course with the cap, 4, removed) should have the spindle 9, placed in the center opening, 7, of the baffle and fastened there by the split ring, 5 36; then the second tubular section, *b*, has its top end entered into the circular rabbet of the first section and cemented fast. The loose weight, 15, should then be inserted into the bottom of the second tubular section 10 and its vertical square opening, 18, connected loosely onto the square lower end, 11, of the said spindle; the float valve, 14, should then be inserted. The upper end of the third or lower section, *c*, should have 15 its reduced part, 37, inserted into the lower end of the second section, *b*, and there secured by cement. Then the lowermost valve, 38, should be placed into the chamber of said third section, and finally the valve-port ring, 20 25, should be inserted and cemented. This completes the assembling of the parts into the tubular shell.

To apply this device to a bottle filled with liquid, a shell comprising the three chambered sections, *a*, *b*, *c*, and having all the internal parts properly assembled, should be inserted down into the neck of a bottle filled with the desired liquid. A small space may be formed within the bottle neck and 25 around one of the tubular sections, for the reception of cement, 42, which when hardened will hold the tubular shell fast and tight in said bottle-neck. The cap, 4, may now be put in position as seen in Fig. 35 1, and the plug, 3, and cork, 5, will fill the nozzle or mouth.

To turn liquid out of the bottle, first remove the cap, and then the liquid contents of the bottle may be partly or entirely 40 emptied, but the bottle can not be refilled.

If the valve, 14, should happen to stick fast to its seat it can be loosened by applying suitable means to the spindle, 9, and turning said spindle. The square upper 45 end, 10, of this spindle is exposed in the top part of the bottle-neck, and is there accessible. The cap itself has a socket, 13, that applies to said spindle end, 10, and by turning the cap the spindle will turn and the 50 valve, 14, will be loosened if stuck.

The parts of this device which prevent refilling can not be removed from the bottle neck without breakage, and as all of said parts are designed to be made of glass or 55 porcelain they will be innocuous, tasteless and harmless to all kinds of liquids particularly to brandy, whisky, gin, wines, cordials and sauces.

Having thus described my invention what 60 I claim and desire to secure by Letters Patent is:—

1. The combination of a bottle-neck; a tubular shell fitted within said bottle-neck and forming the walls of a chamber whose bottom is provided with a port opening; a disk-

valve seating over said port opening, and said valve having an upward-projecting stem and also provided with a cylindric buoyant body fitting around the said stem but leaving its upper end projecting above 70 said body; and a weight inclosed in said chamber and movable longitudinally independent of said body and valve but rotatably connected therewith by said stem projection. 75

2. The combination of a bottle-neck; a tubular shell fitted within said neck and projecting above; a baffle diaphragm within the tubular shell; a valve and port below 80 said diaphragm for permitting the outflow of liquid but preventing its inflow; a removable cap that closes the discharge mouth and which is free to be turned or rotated while in its closed position, and means connecting the cap and said valve, whereby 85 upon turning the cap the valve may be loosened.

3. The combination of a bottle-neck; a tubular shell projecting above the bottle-neck and having a discharge mouth; a diaphragm fixed within the shell below said mouth and said diaphragm forming at its upper side a space within the top part of the shell and said diaphragm having openings; a removable cap closing the discharge 95 mouth said cap being entirely removed when pouring liquid from the bottle; a valve-seat below the said diaphragm and having a port for the outflow of liquid; a valve normally on the seat and which opens 100 and closes said port when a tilting movement of the bottle occurs; and means communicating from the said top space above the diaphragm to the said valve below for loosening the valve should the latter become 105 stuck to its seat.

4. The combination of a bottle-neck having at its top a mouth; a valve and port structure within the said neck—said valve being free to open and close by the tilting 110 action of the bottle; a rotatable spindle mounted in the bottle-neck; means connecting the spindle with the valve; and a cap closing the mouth of the bottle-neck and said cap being connected with the rotatable 115 spindle, whereby the valve may be loosened by turning the cap.

5. The combination of a bottle-neck; a spindle in the neck; a cap which closes the mouth of the neck, connects with spindle and has a rotary movement; a valve and port structure inclosed in the neck—said valve provided with an upward-projecting stem; and means movable longitudinally in the bottle-neck and which forms a loose coupling between the said spindle and the stem of the valve. 120

6. The combination of a bottle-neck; a disk-valve having an upward projecting stem and closing a port; a buoyant body 125

attached to said valve but leaving the upper end of the valve-stem exposed; a weight which is movable independently of the valve but which, when the bottle stands normally upright will serve to press the valve to its seat; a top cap closing the mouth of the bottle and capable of a rotary movement, and means connecting between the top cap and the upper end of the valve stem.

In testimony whereof I affix my signature 10 in presence of two witnesses.

JOHN L. SELLAR.
